UNITED STATES PATENT OFFICE

121,878

DESIGN FOR A NECKTIE BOX OR SIMILAR ARTICLE

George B. Patterson, Garden City, N. Y.

Application May 28, 1940, Serial No. 92,664

Term of patent 7 years

To all whom it may concern:

Be it known that I, George B. Patterson, a citizen of the United States, residing at Garden City, Long Island, in the county of Nassau, in the State of New York, have invented a new, original, and ornamental Design for a Necktie Box or Similar Article, of which the following is a specification, reference being had to the accompanying drawing, forming a part thereof.

The surface ornamentation shown in part in Figures 1 and 2 is continued throughout the areas of said figures now shown plain.

I claim:

The ornamental design for a necktie box or similar article, substantially as shown and described.

GEORGE B. PATTERSON.
